FIG. 1

FIG. 2

FIG. 1 is a perspective view of a combined coaster set and holder showing my new design as viewed from above, one of the coasters having been removed from the holder for sake of illustration, it being understood that the coasters are all substantially identical in appearance; and

FIG. 2 is a perspective view thereof as viewed from below, one of the coasters again being removed from the holder to illustrate the underside of the coasters.

I claim:

The ornamental design for a combined coaster set and holder, substantially as shown and described.
